UNITED STATES PATENT OFFICE.

LEWIS E. ZERBE, OF MONTEZUMA, CALIFORNIA, ASSIGNEE TO WILCO TOOL COMPANY,
OF TORRANCE, CALIFORNIA, A CORPORATION OF CALIFORNIA.

SHAFT BEARING.

Application filed March 22, 1923. Serial No. 386,761.

To all whom it may concern:

Be it known that I, Lewis E. Zerbe, a citizen of the United States, residing at Monteza, in the county of Los Angeles and State of California, have invented a new and useful Shaft Bearing, of which the following is a specification.

This invention relates to crown block bearings which are used on oil-well derricks for supporting the shafts of sheaves, and which are located over the well. The derricks are usually constructed of wood on a foundation that is not too stable, and as the derricks are subjected to enormous strains there is a tendency for the sheaves to get out of alignment with the well hole. These bearings are also exposed to sand that comes up on the sand line, and to sand that is blown off the well during wind storms. On account of the height of the derricks, such bearings should be capable of operating continuously without much attention. The general object of this invention is to produce a bearing which will overcome these difficulties and which will satisfactorily meet these trying conditions; more specifically, to provide a bearing having a construction which will facilitate its adjustment for alignment, and which is provided with improved means for insuring its constant and effective lubrication.

Further objects of the invention will appear hereinafter.

The invention consists in the novel parts and combination of parts to be described hereinafter, all of which contribute to produce an efficient crown block bearing.

A preferred embodiment of the invention is described in the following specification while the broad scope of the invention is pointed out in the appended claims.

In the drawings:

Figure 1 is a perspective view showing an embodiment of the invention.

Fig. 2 is a vertical cross section through the bearing illustrated in Figure 1 and showing a portion of the supporting beam in elevation.

Fig. 3 is a longitudinal section through the bearing shown in Figure 1, showing a portion of the shaft and illustrating the supporting beam in cross section.

I construct the bearing so as to facilitate its attachment and adjustment on a beam 20. For this purpose I provide a plurality of

bolts 32, the lower ends of which are provided with hooks 32^b which engage the beam. When the beam is of Z-form, these hooks engage under the edges of the upper flange.

I also provide the box with means for engaging the beam so as to fix it to the beam, that is to say, I provide means to prevent the box from shifting laterally on the beam. For this purpose I provide the under side of the box with a recess 23, the side faces of which fit to and engage snugly the side edges of the upper flange of the beam.

The box 20 may be provided with means for guiding the bolts when they are shoved up into position and this means is preferably constructed so as to prevent rotation of the bolts when their nuts are being applied to them. For this purpose the lower portions of the bolts are formed with angular or square shanks 24, see Figure 2, which are received in square guide ways 26 in the box. The upper ends of the bolts extend above the upper face 20 of the box and are threaded to receive bolt retainers 32^c in the form of spanner nuts that are screwed down with a spanner wrench as an ordinary nut. Above the bolt retainers 32^c the threaded ends of the bolts extend upwardly through or past the cap 34, and receive nuts 28 which seat on the cap and secure it in place.

In providing for the lubrication of this type of bearing I may provide a reservoir 33 in the box to receive a lubricant and provide the cap 34 with a filling cup 35 having a suitable rain proof lid 36; the bottom of the cup communicates with the reservoir 33 so that by lifting this lid 36 the reservoir may be supplied with lubricant.

In the lower portion of the reservoir a transverse duct 37 is provided which is simply cored in the bottom of the box. The means for raising the lubricant to the exposed face of the shaft 39, in this case, is a capillary member such as a wick 38 extending up from the duct 37, placed so that its upper end touches the upper face or side of the shaft carried in the bearing. The bore of this bearing is formed in the box and is provided with a permanent bushing 40 of Babbitt metal, bronze or other suitable bearing metal.

What I claim is:

1. In a shaft bearing of the kind described, the combination of a beam, a box supported by the beam, hook bolts engag-

ing the beam for securing the box to the beam, a cap on the box secured thereto by the said bolts and the box projecting laterally beyond the beam and provided with 5 depending faces engaging the side of the beam, the bolts extending through the lateral extensions of the box.

2. In a shaft bearing of the kind described, the combination of a beam, a box 10 supported by the beam, hook bolts engaging the beam for securing the box to the beam, bolt retainers carried by the bolts and seating on the box, a cap on the box above the bolt-retainers, and receiving the upper 15 ends of the bolts, nuts on the bolts securing the cap and the box projecting laterally beyond the beam and provided with depending faces engaging the side of the beam, the bolts extending through the lateral exten- 20 sions of the box.

3. In a shaft bearing of the kind described, the combination of a beam, a box 25 supported by the beam, hook bolts engaging the beam for securing the box to the beam, and having angular shanks received by the box for preventing rotation of the bolts when in place, a cap on the box se-

cured thereto by the bolts and the box projecting laterally beyond the beam and provided with depending faces engaging the 30 side of the beam, the bolts extending through the lateral extensions of the box.

4. In a shaft bearing of the kind de- 35 scribed, the combination of a beam, a box supported by the beam, hook bolts engag- 40 ing the beam for securing the box to the beam, said box having extensions on its under side for engaging the sides of the beam to fix the box on the beam, the bolts extending through the extensions and a cap on the 45 box and secured by the said bolts.

5. In a shaft bearing of the kind de- 50 scribed, to be mounted on a beam, the combination of a box formed on its underside with a channel for engaging the beam to fix the 45 box laterally on the beam, hook bolts engag- 55 ing the beam for securing the box vertically to the beam, and a cap on the box secured thereto by the said bolts, the bolts extending through the walls of the channel.

Signed at Torrance, Calif., this 15th day of March 1923.

LEWIS E. ZERBE.
